COLLAR SUPPORT FOR A SLAB

Marshall Long, 10901 Mission Road,
Overland Park, Kans.

Filed Dec. 15, 1961, Ser. No. 67,922

Term of patent 14 years

(Cl. D54—1)

FIG. 1

FIG. 2

FIG. 3

FIG. 4

FIG. 5

FIG. 6

FIG. 1 is a perspective view of a collar support for a slab showing my new design;

FIG. 2 is a top plan view thereof;

FIG. 3 is a bottom plan view thereof;

FIG. 4 is a front elevational view thereof;

FIG. 5 is a side elevational view thereof; and

FIG. 6 is a fragmentary cross-sectional view taken on the line 6—6 of FIG. 2.

I claim:

The ornamental design for a collar support for a slab, substantially as shown.
